UNITED STATES PATENT OFFICE.

NICHOLAS BLUMHOFER, OF FAIRFAX, MINNESOTA.

WAGON-BODY LIFTER.

SPECIFICATION forming part of Letters Patent No. 761,815, dated June 7, 1904.

Application filed August 1, 1903. Serial No. 167,953. (No model.)

To all whom it may concern:

Be it known that I, NICHOLAS BLUMHOFER, a citizen of the United States, residing at Fairfax, in the county of Renville and State of Minnesota, have invented certain new and useful Improvements in Wagon-Body Lifters; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to wagon-body lifters, and has for its object to provide a device of this class which is so constructed that a man single handed can put on or off a wagon-body.

My invention is particularly adapted to put on or take off the running-gear of a wagon the usual hay-racks employed by farmers for carrying hay.

As is of course understood, wagons used in husbandry usually have two or more bodies, one, ordinarily termed a "hay-rack," for carrying hay, while the others are used for other purposes. To put on the running-gear or take off one of these bodies is quite a task, and it is for the purpose of facilitating this operation that I have made my present invention, which consists in novel raising means and in the construction employed for handling and moving the wagon-body horizontally on or off the running-gear.

My invention also consists in certain other novel features of construction and in combination of parts, which will be first fully described and afterward specifically pointed out in the appended claims.

Referring to the accompanying drawings, Figure 1 is a front perspective of my invention. Fig. 2 is a rear perspective of the same. Fig. 3 is a detail view of one of the supporting-arms, showing racks and pinions. Fig. 4 is a sectional view taken on line 4-4 of Fig. 3.

Like numerals of reference indicate the same parts throughout the several figures, in which—

1 is a wagon-body lifter composed of the two horizontal frame-pieces 2, which rest upon the ground. Secured upon said pieces is the

base-plate 3, upon which is secured the lower frame-piece 4, to which are securely fastened the upright standards 5. Supporting said standards are the supports 6, and 7 indicates the upper cross-piece connecting said standards and bracing the same. 55

8 indicates the vertically-movable rack-bars, which are carried and guided between each pair of the upright standards 5, said vertically-movable rack-bars being provided with horizontally-extending forward arms or projections 9, having a groove 10 therein, and said upright standards 5 are provided with an opening 11 in line with said groove, through which the horizontally-movable supporting-arms 12 pass. Secured to said horizontally-extending forward arms 9 are vertically-movable rack-bars 13, housed in casings 14, extending into the ground. 60 65

Referring particularly to Fig. 2, 14' indicates a shaft carrying a series of pinions 15, which mesh with the vertically-movable rack-bars 8, Fig. 3, and which carries a sprocket-wheel 16. 70

In Fig. 1, 17 indicates a shaft carrying a series of pinions 18, which mesh with the vertical rack-bars 13, Fig. 3, and 19 indicates a sprocket-wheel on said shaft. A chain 20 connects said sprocket with the sprocket 16 on shaft 14', and a large fly-wheel 21 is secured on the shaft 17, said wheel having a handle 22 and a series of radially-extending pins 23 around the periphery of said wheel. 75 80

A longitudinally-movable sliding brake-bar 24, secured in straps 25, is utilized as a brake or in order to lock the machine by sliding said rod into engagement with the pins 23 of the wheel 21. (Dotted lines, Fig. 2.) 85

Referring now to Fig. 1, 26 indicates a shaft carrying a series of sprockets 27, which mesh with the racks on the horizontally-movable supporting-arms 12, and I provide a crank or handle 27' on the end thereof to revolve said shaft. 90

Having thus set forth the several parts of my invention, its operation is as follows: The device is placed, as shown, with the casings 14, wedge-pieces 28, and pins 29 extending into the ground. When it is desired to raise a wagon-body off the running-gear, the wheel 100

21 is revolved, which turns the shafts 17 and 14' and pinions 18 and 15, which engage the rack-bars 8 and 13 to lower the same, which also lowers the horizontally-movable supporting-arms 9. When said arms have been lowered to a point under the wagon-body, the crank or handle 27' is turned, which revolves the shaft 26 and pinions 27, in engagement with the said arms, moving the same horizontally under the wagon-body. When said arms are well under the body of the wagon, so as to properly support the same, the wheel 21 is again turned, so as to raise the rack-bars 8 and 13 and raise the supporting-arms carrying the wagon-body up off the running-gear. When said body has been raised clear off the running-gear, the brake-rod 24 is slid into engagement with the pins 23 of the wheel 21, thus locking the machine carrying the wagon-body. The running-gear is then moved from under the wagon-body, which may be left in its raised position and replaced upon the running-gear whenever again required.

Having thus fully described my invention, I do not wish to be understood as limiting myself to the exact construction herein set forth, as various slight changes may be made therein by those skilled in the art, which would fall within the limit and scope of my invention, and I consider myself clearly entitled to all such changes and modifications.

What I claim as my invention, and desire to secure by Letters Patent of the United States, is—

1. In a wagon-body lifter, the combination of suitable framework, vertical rack-bars, forwardly-extending arms thereon, horizontally-movable supporting-arms carried by said forwardly-extending arms, shafts and pinions carried thereby to mesh with said rack-bars and horizontally-movable supporting-arms and means for moving the same substantially as described.

2. In a wagon-body lifter, the combination of suitable framework, vertical rack-bars, horizontally-movable supporting-arms carried by said vertical rack-bars, and means for raising and lowering said rack-bars, and independent means for moving said supporting-arms.

3. In a wagon-body lifter, the combination of suitable framework, a series of vertical movable bars, horizontally-movable supporting-arms adapted to be raised or lowered by said vertically-movable bars, and means for moving said supporting-arms independent of the movement of said vertical bars.

In testimony whereof I affix my signature in presence of two witnesses,

NICHOLAS BLUMHOEFER.
